UNITED STATES PATENT OFFICE.

HENRY EDWARD PELLETIER, OF CLARKSBURG, WEST VIRGINIA.

NUT LOCK.

Application filed September 12, 1923. Serial No. 662,245.

To all whom it may concern:

Be it known that I, HENRY E. PELLETIER, a citizen of the United States, residing at Clarksburg, in the county of Harrison and 5 State of West Virginia, have invented certain new and useful Improvements in Nut Locks, of which the following is a specification, reference being had to the accompanying drawings.

10 This invention relates to certain improvements in nut locks and it is an object of the invention to provide novel and improved means whereby a nut, when applied to the bolt, is held against retrograde movement 15 and particularly as may be occasioned by vibration.

It is also an object of the invention to provide novel and improved means of this general character which operates to advantage 20 in the proper maintenance of the nut upon the bolt but which can be easily rendered inoperative or ineffective when it is desired to remove the nut.

The invention consists in the details of 25 construction and in the combination and arrangement of the several parts of my improved nut lock whereby certain important advantages are attained and the device rendered simpler, less expensive and otherwise 30 more convenient and advantageous for use, as will be hereinafter more fully set forth.

The novel features of my invention will hereinafter be definitely claimed.

In order that my invention may be the 35 better understood, I will now proceed to describe the same with reference to the accompanying drawings, wherein:—

Figure 1 is a view in elevation illustrating a nut lock constructed in accordance 40 with an embodiment of my invention;

Figure 2 is also a view in elevation but in one quarter relation to that shown in Figure 1;

Figure 3 is a view in top plan of the device as illustrated in Figure 1;

Figure 4 is a sectional view taken substantially on the line 4—4 of Figure 1; and

Figure 5 is a view in perspective of the holding or retaining member unapplied.

50 As disclosed in the accompanying drawings, B denotes a bolt provided with a plurality of circumferentially disposed grooves 1 intersecting a thread 2 thereof, each of said grooves being of a ratchet type. Associated 55 with the bolt B in a conventional manner is the nut N.

The nut N is provided on one side with a transversely disposed aperture 3 in communication with the bore thereof. Communicating with the outer portion of the opening 60 3 is a groove or channel 4 produced in the outer face of said side provided with the opening 3. This groove or channel 4 has its outer end in communication with a groove or channel 5 provided in the adjacent facets 65 or substantially in a direction transverse of the bore of the nut, both of said grooves or channels 4 and 5 being disposed longitudinally of the associated facet. The groove or channel 5 terminates at substantially the 70 axial center of the facet in which it is produced and the inner end of said groove or channel 5 is continued by an outwardly directed channel or groove 6 substantially at right angles to the groove or channel 5, the 75 outer end of the groove or channel 6 being open.

The holding or retaining member M is formed from a single blank of material possessing a certain degree of inherent resiliency, and said member comprising the angularly related arms 7 and 8 adapted to be received within the grooves 4 and 5 respectively. The arm 7 is continued by an inwardly directed arm 9 which, when the 80 member M is in applied position, is disposed through the opening 3 and is adapted to engage within a groove 1 whereby the applied nut N is effectively held against retrograde turning movement with respect to the 85 bolt B yet permitting requisite turning movement of the nut N in the opposite direction.

The outer end portion of the arm 8 of the member M is continued by a laterally disposed arm 10 which is adapted to be received, when the member M is applied, within the groove or channel 6, said arm 10 being of a length to extend beyond the outer or open end of said groove or channel 6 so 100 that when it is desired to release the nut N for retrograde rotation relative to the bolt B it is only necessary to apply relatively slight pressure to the extended portion of the arm 10, the size or diameter of the opening 3 being such to readily permit the requisite swinging movement of the member M or more particularly the arm 9 in a direction substantially transverse to the bore of the nut N to readily facilitate its entire 105 removal from the nut N. This constitutes an important feature of the present inven-

- tion as with the member M entirely removed the nut N may be turned upon the bolt B without hinderance or obstruction with any type of wrench or kindred tool. During 5 the period the nut N is being applied to the bolt B, the member M may be unapplied. When the nut has been properly adjusted the member M is then forced into working 10 position upon the nut N although an applied member M will offer no hinderance or obstruction to the application of the nut. If the member M is not applied during the setting operation of the nut N it is placed 15 in position upon substantially proper adjustment of the nut and if the opening 3 is not in position to permit the arm 9 to engage within a groove 1 further turn may be given to the nut N with the applied member M to effect such interengagement.
- 20 The grooves or channels 4 and 5 are of such depth that when the member M is in applied position the arms 7 and 8 of said member M are entirely confined or housed within said grooves or channels so that no 25 obstruction is offered by the applied member to a socket wrench or other tool which may be employed in applying the nut to the bolt B and this is of particular advantage in connection with automobiles or 30 other work where the bolt is positioned at a place not conveniently accessible.

From the foregoing description it is thought to be obvious that a nut lock constructed in accordance with my invention is 35 particularly well adapted for use by reason of the convenience and facility with which it may be assembled and operated, and it will also be obvious that my invention is susceptible of some change and modification 40 without departing from the principles and spirit thereof and for this reason I do not wish to be understood as limiting myself to the precise arrangement and formation of the several parts herein shown in carrying 45 out my invention in practice except as hereinafter claimed.

I claim:—

1. In a nut locking device, a bolt having a groove extending therealong, a nut engageable with the bolt, said nut having an opening disposed through a side thereof and in communication with the bore thereof, the

periphery of the nut being provided with a groove in communication at one end with the opening and disposed in a direction 55 transversely of the opening, the opposite end of said groove being continued by an angularly disposed groove opening through an end face of the nut, a holding member adapted to seat within the peripheral groove 60 of the nut and having an arm at one end insertible through the opening of the nut for engagement within the groove of the bolt and also with an arm extending within the open groove of the nut, said second arm being of a length to terminate beyond the 65 face of the nut through which said second groove opens when the locking member is applied, said extended portion of the second named arm providing means for disengag- 70 ing the holding member from the nut.

2. In a nut locking device, a bolt having a groove extending therealong, a nut engageable with the bolt, said nut having an opening disposed through a side thereof and 75 in communication with the bore thereof, the periphery of the nut being provided with a groove in communication at one end with the opening and disposed in a direction transversely of the opening, the opposite end 80 of said groove being continued by an angularly disposed groove opening through an end face of the nut, a holding member adapted to seat within the peripheral groove 85 of the nut and having an arm at one end insertible through the opening of the nut for engagement within the groove of the bolt and also with an arm extending within the open groove of the nut, said second arm being of a length to terminate beyond the 90 face of the nut through which said second groove opens when the locking member is applied, said extended portion of the second named arm providing means for disengag- 95 ing the holding member from the nut, the opening through the side of the nut being of a diameter to permit swinging movement of the first named arm in a direction trans- 100 verse to the bore of the nut to facilitate the application and removal of the holding member.

In testimony whereof I hereunto affix my signature.

HENRY EDWARD PELLETIER.
